UNITED STATES PATENT OFFICE.

GUSTAV MÖLLER, OF BERLIN-CHARLOTTENBURG, GERMANY.

APPARATUS FOR PUMPING LIQUIDS.

1,197,755.

Specification of Letters Patent. Patented Sept. 12, 1916.

Application filed February 24, 1912. Serial No. 679,675.

To all whom it may concern:

Be it known that I, GUSTAV MÖLLER, a subject of the King of Prussia, residing at Berlin-Charlottenburg, in the Kingdom of Prussia and German Empire, have invented new and useful Improvements in Apparatus for Pumping Liquids, of which the following is a specification.

My present invention relates to improvements in centrifugal pumps adapted to be driven by high speed engines, such as steam turbines, or the like.

In a centrifugal pump having a given discharge head the external diameter of the pump depends upon the speed of rotation, so that, according as the number of revolutions increases, the diameter of the pump decreases. If, for example, a centrifugal pump for a small discharge head is driven directly by a high speed engine, such as a turbine, or electromotor, the external diameter of the pump must of course be very small. For larger quantities of liquid the drawback would then arise that the diameter of the inlet, or suction, opening would have to be very large, and would eventually much exceed the external diameter, because, for theoretical and practical reasons, the inlet speed cannot much exceed ten feet per second, so that a practically useful pump cannot be constructed. Attempts have been made to overcome this drawback by dividing the pump into several parallel working disks on one and the same shaft, but there is also a limit to such a division, owing to the great complication of the pump casing, and the unfavorable conditions for guiding the water, as well as the difficulty of properly supporting the long shaft.

My present invention consists, in coupling the high speed rotating driving engine or motor with a centrifugal pump adapted to force a comparatively small quantity of liquid to a very great height, and in conducting the liquid from said pump to a turbine in which the energy contained therein is utilized to such an extent that the water issuing from said turbine still has sufficient energy to rise up to the height to which it has to be forced. Said turbine is coupled with the main centrifugal pump, and is so constructed that its speed of rotation conforms with the normal speeds of rotation of centrifugal pumps, that is said pump rotates at the speed at which a large quantity of liquid can be forced with good efficiency.

The object of the invention is, therefore, to enlarge the external diameter of the centrifugal pump disk by reducing the number of revolutions described.

In the accompanying drawing illustrating the invention by way of example: Figure 1 is a diagrammatic representation of the manner of connecting the various apparatus. Fig. 2 is a section through a centrifugal pump, in which a one-sided centrifugal pump disk, that is the so called low pressure pump, is combined in one casing with the turbine by which it is driven and with the driving or so called high pressure pump, which supplies water under pressure to said turbine. Fig. 3 is a section on the line A—B in Fig. 2, Fig. 4 is a section through a one-sided combined pump, in which a feed pump coupled directly with the slowly rotating pump is adapted to deliver the liquid to the high pressure pump with a certain initial speed. Fig. 5 shows a section through a double-sided combined pump, in which a feed pump is provided to deliver liquid to both sides of the high pressure pump.

1 is the driving engine (a high speed steam turbine, gas turbine, electromotor, or the like), to the shaft 2 of which is directly coupled the high pressure pump 3, which sucks a comparatively small quantity of liquid out of the pipe 4 through a branch pipe 5, and forces the same at a high pressure through the pipe 6 to the turbine 7 which is of the reactionary type. After leaving the turbine 7 the water flows through the branch pipe 8 to the pressure main 10 and still has sufficient energy to attain the same height as the liquid forced by the low pressure pump 9. The low pressure pump 9 is coupled with the turbine 7 by which it is driven. Said low pressure pump sucks the water out of the suction pipe 4 and forces it into the pressure pipe 10, in which the liquid from the turbine 7 also flows. The turbine is coupled with the low pressure pump 9 by the shaft 11.

In the construction shown in Figs. 2 and 3 the low pressure pump 9 is combined with the turbine 7 and arranged in one and the same casing 12. In said casing the high pressure pump 3 is also provided and the arrangement is of such a character that the driving shaft 2 of the high pressure pump is in a line with the shaft 11 of the low pressure pump. The turbine 7 and the low pressure pump 9 are surrounded by the well

known diffuser 13, through which the liquid is forced into the pressure pipe 10.

In the construction shown in Fig. 4 the arrangement is such that a special feed pump 14 is provided for the high pressure pump 3, which feed pump together with the low pressure pump 9 sucks liquid out of the suction pipe 4 and feeds the same to the high speed high pressure wheel 3.

10 The construction illustrated in Fig. 5 is identical in principle with that shown in Fig. 4, the only difference being that both the high pressure and the low pressure pumps are constructed double-sided.

15 The operation of the invention will be clear from the drawing and from the above specification.

The advantages obtained by the invention are (a) for the high pressure pump: a considerably larger external diameter and smaller internal diameter, because the discharge head is increased and the quantity of the liquid is reduced, (b) for the low pressure pump: likewise increase of the external 25 diameter by lessening the number of revolutions, and, in addition, an improvement of the efficiency, so that for the entire combination the drawbacks of high speed pumps of this kind are effectively overcome.

30 In practice the concentric arrangement of the pumps inside one casing, thus without a high pressure main, will probably be chosen. The advantage is that the energy imparted to the liquid in the high pressure disk is 35 utilized in the turbine wheel without any previous transformation of velocity into pressure by which considerable loss would be entailed. Moreover, the casing is then quite as simple as in the ordinary double-sided centrifugal pumps.

The turbine 7 in the described arrangement is always referred to as a reactionary turbine, which means, that the cross-section of the fluid channels or passages is larger at 45 the inlet of the turbine than at the outlet, so that as the pressure of the fluid during its passage through the turbine is decreased the velocity must increase. In this manner it is positively avoided, that any translation 50 of velocity into pressure shall take place in any part of the turbine, which always reduces the operating rate as a result of the accompanying whirling and irregularities in the fluid. The pressure, which is necessary 55 to meet the requirements at the outlet of the whole apparatus should only be generated through the centrifugal force in the high speed pump, in contrast to the known so called rotary diffusers in which the opposite 60 takes place. In this manner it is provided that the turbine 7 produces, as a reactionary turbine, a better operating rate than those

apparatuses which are already known in the art as reactionary turbines.

The turbine wheel may be provided in 65 well known manner with several series of blades, in order to obtain a higher number of revolutions, and said turbine wheel may be constructed on any desired system. Further, two or more of the apparatus described 70 can be arranged parallel to each other, or a high pressure pump may be caused to act on several turbine wheels, or several high pressure pumps may be caused to act on a single 75 turbine wheel. The low pressure pump can also be divided into a number of parallel working pumps. Further, several entire plants may be combined in series in order to increase the purchase, if found to be of advantage.

80 What I claim and desire to secure by Letters Patent of the United States is:—

1. The described apparatus for pumping liquids, comprising in combination, a casing, a high pressure pump element rotatable in 85 said casing, a turbine wheel in said casing rotatable independently of said high pressure pump element and adapted to be driven by the fluid from the latter, and a low pressure pump element carried by said turbine 90 wheel for pumping the main fluid body, said high pressure pump element drawing its fluid supply from said main fluid body.

2. The described apparatus for pumping liquids, comprising in combination, a casing, 95 a low pressure centrifugal pump element mounted in said casing and adapted to lift a comparatively heavy fluid body, a turbine carried by said low pressure centrifugal pump element and adapted to drive the latter, and a high pressure pump element also mounted in said casing and adapted to deliver a comparatively small quantity of water under sufficient pressure to drive said turbine.

105 3. The described apparatus for pumping liquids, comprising in combination, a casing, a high pressure pump disk, rotatable in said casing, a turbine wheel surrounding said high pressure pump disk and adapted to receive fluid under high pressure from said high pressure pump disk, and a second pump disk carried by said turbine wheel and adapted to be driven by the latter at a speed 110 to deliver a comparatively large quantity of fluid under a lower pressure.

115 In testimony whereof I have signed my name to this specification in the presence of two subscribing witnesses.

GUSTAV MÖLLER.
